PROCESS OF DEWAXING OILS

Eddie M. Dons and Dwight B. Mapes, Tulsa, Okla.,
assignors to Mid-Continent Petroleum Corporation,
Tulsa, Okla., a corporation of Delaware

Application May 3, 1934, Serial No. 723,662

4 Claims. (Cl. 196—18)

This invention relates to processes of dewaxing oils, and more particularly to the dewaxing of oils wherein a normally gaseous hydrocarbon, such as propane, is employed.

5 There are substantial variations in the nature of wax-containing oil stocks, and many valuable lubricating oil stocks cannot be economically dewaxed by the usual methods which comprise diluting the oil with naphtha, chilling the result-

10 ant solution, and centrifuging, or slowly filtering, the wax from the oil.

It has been proposed to employ propane as a chilling medium and a diluent during the dewaxing of oils. Propane is a naturally occurring hydrocarbon which is a gas at ordinary conditions of temperature and pressure, but can be converted into a liquid by subjecting the same to a relatively high pressure.

Substantially all lubricating oil stocks may be dewaxed with the proper use of propane, and such a process will more completely remove the wax than the old methods now in common use.

Lubricating oil stocks containing wax, when warm, can be readily dissolved in liquid propane, and a solution of undewaxed oil and propane can be chilled by evaporating some of the propane from the solution, the propane taking up heat from the solution as the propane passes into a vapor state. As the solution is chilled, wax crystals form which can be completely removed from the solution by filtering if the proper conditions of chilling have been maintained.

The method of chilling the solution of oil and propane is very critical, and if the solution has not been properly chilled the wax cannot be successfully filtered from the solution.

Due to the critical condition of chilling, it has been thought that the batch operation of chilling was the only manner in which the proper chilling could be obtained. A batch operation provides satisfactorily conditions for chilling the solution of oil and propane, as the propane may be released from a large volume of the solution at the desired rate to precipitate the wax in the best form for filtering.

However, in a large commercial dewaxing plant, such batch operations have serious disadvantages. Large vessels of alloy steel subjected to a high pressure must be repeatedly warmed and then chilled to about -40° F., which is an uneconomical and inefficient procedure. Moreover, the hazards involved in such rapid temperature changes in high pressure vessels, necessitates a very expensive construction.

55 In addition to the foregoing disadvantages the

volume of propane required is large and the production slow.

An object of our invention, therefore, is to provide a continuous process for dewaxing an oil with propane wherein a constantly flowing stream of the solution of oil and propane is continuously chilled at the desired rate and under conditions that result in a chilled solution from which the wax can readily be removed by filtration.

Another object of this invention is to provide a process wherein the temperature at any point in the system will be practically constant so as to avoid the strain of frequent and rapid temperature changes.

A further object is to provide a simple and relatively inexpensive process for dewaxing an oil with propane while obtaining a large production of dewaxed oil with a relatively small quantity of propane in the system.

With the foregoing and other objects in view, the invention comprises the novel method hereinafter more specifically described and shown in the accompanying drawings, which illustrate one form of the invention. However, it is to be understood that the invention comprehends changes, variations and modifications which come within the scope of the claims hereunto appended.

In the art of dewaxing oils with propane, it is well known that sudden or shock chilling by flash expansion of the solution of oil and propane results in precipitation of wax in a form that will not filter freely. The development of a continuous process must, therefore, provide for the desired chilling of the oil without sudden expansion or evaporation of propane from the solution.

We have found that the required gradual reduction in temperature and pressure can be obtained by passing the solution through an elongated passageway, preferably a coil of pipe, of such length and diameter that the pressure necessary to maintain relatively warm propane in a liquid state is very gradually reduced to atmospheric or nearly atmospheric pressure. The chilling passageway may be of uniform diameter throughout its length, but a more uniform pressure drop and more uniform rate of chilling is obtained by gradually increasing the diameter of the passageway toward the low pressure end. As the solution flows through the elongated chilling passageway, a gradual loss of pressure occurs due to resistance to flow in the passageway. Since the pressure is very gradually reduced as the solution passes through the passageway, propane will continually be passing from the liquid to the

vapor state, thus taking up heat from the solution. This propane vapor flows through the passageway with the solution, probably more or less in the form of foam, and as the volume increases due to increased vapor phase, the diameter of the pipe is preferably increased.

Advantages are gained by discharging regulated quantities of propane gas at various intervals along the length of the chilling passageway, to effectively control the gradual reduction in pressure, this being especially true if the passageway is uniform in diameter throughout its length. However, the preferred form of the invention is to use a coil of gradually increasing diameter, and when a very accurate control is desired, portions of the vapor may be discharged at various points in the coil.

Fig. 1 is a diagrammatical view of a system embodying the features of this invention.

Fig. 2 is a detail view of a chilling coil adapted for use in the system.

As an illustration of one form of the invention, we have shown a system wherein undewaxed oil is continuously withdrawn from a storage tank 1 by pump 2 and passed through heater 3, and conductors 4 and 5 into a mixing nozzle 6. The oil is preferably warmed in the heater 3 to a temperature at which it is freely soluble with liquid propane, such as 175° F.

Liquid propane is continuously withdrawn from storage tank 1 by pump 8 and forced under a pressure sufficient to maintain the propane in a liquid condition through conductors 9, 10 and 5 to the mixing nozzle 6 where it is intimately mixed with the warm oil from storage tank 1. The warm solution, which may be about one part oil to three parts propane, may be transmitted to a mixing nozzle 11 where it is thoroughly mixed with a cold stream of filter wash containing about two parts propane and a very small quantity of oil obtained from a source to be hereinafter described. The resultant solution is transmitted through the conductor 5, which is provided with a pressure reducing valve 5' to a solution reservoir 12. As a result of the addition of the relatively cold filter wash the solution upon entering the reservoir 12 will be at a temperature of about 60° F. and contains approximately one part oil to five parts propane.

From the reservoir 12 a stream of the solution may be continually forced to one or more of the chilling coils 14. Each of the chilling coils has a sufficient length and diameter to provide a gradual decrease in pressure on the solution whereby a portion of the propane is evaporated to effect a gradual reduction in the temperature as the stream passes through the pipe or passageway 14.

As a specific illustration of one form of a chiller, we have shown in Fig. 2 a series of connected pipes having different diameters to provide an elongated passageway having a gradual increase in diameter. Starting at the high pressure end 13 of the chiller 14, the connected pipes may have the following dimensions, 25 feet of $\frac{1}{8}$ inch pipe as shown at A, 100 feet of $\frac{1}{16}$ inch pipe shown at B, 100 feet of $\frac{1}{4}$ inch pipe shown at C, 100 feet of $\frac{5}{16}$ inch pipe shown at D, 80 feet of $\frac{3}{8}$ inch pipe shown at E, 40 feet of $\frac{1}{2}$ inch pipe shown at F, and 40 feet of $\frac{5}{8}$ inch pipe shown at G.

To provide for a very accurate control of the gradual reduction in pressure on the stream passing through the coil, or elongated passageway, 14, we have shown vapor chambers 16 interposed at intervals along the coil. Each of these

chambers 16 is provided with a discharge pipe 17 from which propane vapor may be transmitted through conductors 18, 19 and 20 (Fig. 1) to a compressor 21, which forces the propane through condenser 22 and thence through pipes 23 and 24 to the propane storage tank 7. Each of the discharge pipes on the respective vapor chambers 16 (Fig. 2) may be provided with a valve 25 so that the operator may regulate the discharge of the propane vapor to maintain the desired gradual reduction in pressure on the solution. The pressures at different points in the chiller are indicated by gauges 26 (Fig. 2).

The continuous stream of solution entering the coils 14 from the reservoir 12 may be under a pressure of about 81 pounds per square inch and is gradually reduced so that the solution leaves the coils at about atmospheric pressure.

The reservoir 12 may be provided with a propane vapor outlet pipe 59 leading to the conductor 19 from which the vapor is returned through conductors 20, 23 and 24, and compressor 21, to the storage tank 7. The outlet pipe 59 on reservoir 12 is provided with a valve 59' which may be regulated to maintain the desired pressure on the solution in the reservoir 12, and also the pressure on the solution at the inlet pipes 13 of the chilling coils.

To provide for variations in the capacity of the system, any one of the coils 14 may be dispensed with by closing valves 15 and 15' associated therewith.

The solution leaving the chilling coils 14 may have been gradually reduced by the evaporation of propane to a temperature from -40° to -44° F., and is transmitted through conductors 27 and 28 to a receiver 29. The vaporized propane is separated from the solution in the receiver 29 and is removed through conductors 30 and 28 leading to the compressor 21, and returned to the propane storage tank 7 through conductors 23 and 24.

The cold solution of propane and oil in the receiver 29 is forced through conductor 31, and one of the branch conductors 32 by the pump 33 to one of the filters 34. The branch conductors 32 are provided with valves 35 so that the solution may be diverted from one filter to the other when the filter in service becomes clogged with wax.

The cold wax free solution flows from filters 34 through a conductor 36 to a receiver 37 from which it is pumped through conductor 38 to a solvent recovery station 39. At the solvent recovery station 39 the propane may be recovered by any suitable method, such as by heating the solution, reducing the pressure on the heated solution, and stripping with live steam. The recovered propane is withdrawn through a conductor 40, leading to the conductor 20 and, after being condensed, is returned to the propane storage tank 7. The dewaxed oil passes from the solvent recovery station through a pipe 42, to a storage tank 43.

As previously stated, the cold solution of propane and oil in receiver 29 may be transmitted to either of the filters 34, so that when the filter in service becomes clogged with wax the other filter is available to prevent an interruption of the continuous sequence of the system.

When one of the filters becomes clogged, the wax therein is preferably treated with propane to wash the oil from the wax cake in the filter.

To provide for the removal of the oil from the wax in the filter out of service, propane from

storage tank 7 may be passed through conductors 9 and 45 to propane chilling coils 44. The liquid propane leaving storage tank 7 may be at 100° F. It is, therefore, preferably cooled to about 0° F. at a heat exchanger 46, while flowing through the conductor 45. The chilled oil passing from the receiver 37 to the propane recovery station may be advantageously used as the chilling medium in the heat exchanger 46. By closing a valve 47 in the conductor 38 and opening valves 48 in a conductor 49 passing through the heat exchanger 46, the cold solution will be diverted through said heat exchanger.

The propane, upon leaving the chilling coils 44, may be at a temperature of -40° to -44° F., and is transmitted to a reservoir 50. The gaseous propane in said reservoir 50 may be compressed and returned to the storage tank 7 through return conductors 51, 20, 23 and 24. The cold liquid propane may be pumped from the reservoir 50 through pipe 52, and by regulating the valves 53 and 35 in the respective branch conductors 32, the propane may be passed into the filter out of service to wash the oil from the wax cake.

The cold filter wash passes from either of the filters 34, through a pipe 54, and a pipe 55 to a reservoir 56 from which the cold filter wash containing about two parts propane and a very small quantity of oil is pumped through a conductor 57 to the fresh stream of solution flowing through conductor 5 so as to cool the fresh solution passing to reservoir 12 and chilling coils 14.

The wax and any propane contained therein may be transmitted from either of the filters 34 by pipes 58 and 60 to a wax receiver 61. From the receiver 61, the wax may be transmitted through a pipe 70 to a propane recovery station 62 similar to the propane recovery station 39. The recovered propane is returned to the storage tank through conductors 63, 20, 23 and 24. The wax passes from the solvent recovery station through a conductor 65 to a storage reservoir 64.

If it is found desirable to add cold liquid propane to the chilled oil solution in the receiver 29, propane from reservoir 50 may be added in the desired quantity, through pipes 66 and 28 by a regulation of a valve 67 in the pipe 66.

As an example of the results obtained by a process and apparatus conforming to this invention, we treated a wax-containing heavy lubricating oil distillate with the following specification.

55 Gravity	24.0
Flash	495
Fire	560
Viscosity at 210° F.	68.5
60 Cold test	92

This stock was dissolved in propane in the ratio of one part stock to five parts of propane by volume and allowed to expand through the chilling coil, entering at 81 pounds pressure and expanding to atmospheric pressure at the outlet. The expanded solution was then filtered through No. 8 canvas, and the propane evaporated from the stock.

70 Gravity	23.5
Flash	490
Fire	560
Viscosity at 210° F.	75
75 Cold test	18

A filter rate of approximately two gallons of stock per square foot per hour was obtainable at ten pounds filter pressure.

While we have given a specific illustration of one process and apparatus, it is understood that numerous changes and modifications may be made without departing from the spirit of this invention, as set forth by the claims.

It is also understood that the term propane, does not necessarily imply a pure propane, as propane is employed to cover a mixture of propane and other hydrocarbons. For example, a mixture comprising about 80 per cent propane and about 20 per cent of ethane and butanes is quite satisfactory for carrying out this invention.

As previously stated, propane is a normally gaseous hydrocarbon, and in the preferred form of this invention we prefer to use propane as the normally gaseous hydrocarbon for treating the oil. However, other normally gaseous hydrocarbons include ethane, propylene, and isobutane.

This invention provides a very effective and efficient process for the continuous dewaxing of an oil with a normally gaseous hydrocarbon. The hazard of high pressure vessels, except for storage purposes, is eliminated. The equipment employed to carry out this process is not subjected to the strain of frequent temperature changes, as the temperature at any given point in the system is practically constant after the system is in operation.

The total volume of propane in the system is relatively small and the production of dewaxed oil relatively large. Moreover, the cost of the plant is relatively inexpensive and the dangers of the usual batch propane dewaxing plants are materially reduced.

We claim:—

1. The process of dewaxing oils which comprises dissolving a wax-containing oil in propane while subjecting the solution to a pressure sufficient to maintain the propane in a substantially liquid condition, forcing a continuous stream of the resultant solution through an elongated passageway to gradually evaporate propane from the solution, thus providing a gradual decrease in the temperature of the solution as it progresses along said passageway, filtering the congealed wax from the oil, washing the congealed wax with cold liquid propane to remove oil therefrom, and transmitting the resultant cold liquid propane into said continuous stream at a point in advance of said elongated passageway so as to suddenly cool said continuous stream before it reaches said passageway.

2. The process of dewaxing oils which comprises dissolving a wax-containing oil in a liquefied normally gaseous hydrocarbon, suddenly cooling the resultant solution by introducing a stream of chilled normally gaseous hydrocarbon liquid into a stream of said solution, thereafter precipitating wax from the cooled oil while forcing a stream of the resultant material through an elongated passageway to provide a gradual decrease in pressure on the flowing stream and a gradual evaporation of a portion of the normally gaseous hydrocarbon, and separating the precipitated wax from the oil.

3. The process of dewaxing oils which comprises dissolving a wax-containing oil in propane while subjecting the solution to a pressure sufficient to maintain the propane in a substantially liquid condition, suddenly cooling the resultant solution by introducing a stream of chilled propane into a stream of said solution, thereafter precipitat-

ing wax from the cooled oil while forcing a stream of the resultant material through an elongated passageway to provide a gradual decrease in pressure on the flowing stream and a gradual evaporation of a portion of the propane, and separating the precipitated wax from the oil.

4. The process of dewaxing oils which comprises dissolving a wax-containing oil in propane while subjecting the solution to a pressure sufficient to maintain the propane in a substantially liquid condition, suddenly cooling the resultant solution by introducing a stream of chilled nor-

mally gaseous hydrocarbon liquid into a stream of said solution, thereafter precipitating wax from the cooled oil while forcing a stream of the resultant material through an elongated passageway having a gradual increase in diameter to provide a gradual decrease in pressure on the flowing stream and a gradual evaporation of a portion of the propane, and separating the precipitated wax from the oil.
